UNITED STATES PATENT OFFICE.

OLIE MULLINS, OF TERRE HAUTE, INDIANA, ASSIGNOR OF ONE-HALF TO MILTON T. HUTTS, OF TERRE HAUTE, INDIANA.

WRENCH.

1,083,851.

Specification of Letters Patent.

Patented Jan. 6, 1914.

Application filed August 12, 1913. Serial No. 784,328.

To all whom it may concern:

Be it known that I, OLLIE MULLINS, a citizen of the United States, residing at Terre Haute, in the county of Vigo and State of Indiana, have invented new and useful Improvements in Wrenches, of which the following is a specification.

The present invention relates to improvements in wrenches; and one of the objects 10 in view is to provide a wrench of cheap and simple construction, consisting of few easily assembled parts, capable of fine adjustment and which may be readily applied to a nut to operate upon the nut.

15 A further object of the invention is the provision of a wrench comprising a stationary jaw having a movable jaw slidable upon the shank of the said stationary jaw, the movable jaw being provided with a pivoted member which carries a screw that co-acts with the threads of the shank of the movable jaw, and the said screw carrying member being at all times under the tension of a spring to force the said screw into engagement with the teeth of the shank, and to further provide means whereby the said screw carrying members may be swung out of engagement with the threads to permit of the quick adjustment of the wrench as well 25 as to lock the said element upon the movable jaw to retain the screw in operative engagement with the threads of the shank.

With the above recited objects in view, and others which will appear as the nature 30 of the invention is more fully understood, the improvement resides in the construction, combination and arrangement of parts set forth in the following specification and falling within the scope of the appended claim.

40 In the drawing: Figure 1 is a view of a wrench constructed in accordance with the present invention, the dotted lines illustrating the position of the screw carrying member when the latch has been operated to permit of the same being swung to bring its screw out of engagement with the threads of the shank of the wrench, Fig. 2 is a central longitudinal sectional view taken through the movable jaw and the members 45 carried by the said movable jaw, Fig. 3 is a perspective view of the screw carrying member, and Fig. 4 is a similar view of the latch.

In the drawing, the numeral 1 designates the wrench in its entirety. The wrench includes a stationary jaw 2 which is provided

with a reduced angular shank 3, and the said shank has, what may be termed, its upper face provided with transversely arranged teeth 4, and is also provided with a removable handle 5.

60 The numeral 6 designates the movable jaw. This jaw is formed with a longitudinally extending passage 7 for the reception of the shank 3, the jaw being further provided adjacent its engaging face and above its passage 7 with a depressed portion or pocket 8, and the rear portion of the jaw, to the rear of its pocket and at the upper portion of said jaw terminates in an angular wall 9, the said wall being parallel with the 70 engaging face of the jaw, and so disposed vertically of the jaw when the wrench is in the position illustrated in the figures of the drawing. The wall 9 terminates with the longitudinally extending side walls 10 75 formed by the passage 7, and the said side walls have their ends projected and bridged, as at 11. The side walls are disposed below the upper walls of the passage, so that the angular wall 9 partially enters the said passage, and the bridge 11 is slotted in a plane with the inner surfaces of the side walls to provide a continuation of the passage. The end of the jaw provided with the bridge 11 is formed, at the lower wall of said movable 80 jaw, with a transversely arranged notch 12.

85 The angular wall 9 is centrally formed with a slot 13, and the pocket 8 is adapted to receive a helical pressure spring 14, which is adapted to have one of its ends enter a 90 groove provided upon an annular head 15 which is provided upon one end of an arched member 16, and the said arched member is connected with a tongue 17 provided upon one end of a screw carrying member 18. The tongue 17 is centrally formed upon one of the ends of the said member 18 and is secured within the notch through the medium of a pivot 19 which is arranged transversely 95 of the jaw 6.

100 The end of the wrench has its walls which are provided upon the opposite sides of the tongue 17 and which may be designated by the numerals 20, normally contacting with the angular wall 9 of the jaw 6, and the said member is provided with a transverse opening within which is mounted for rotation a worm or screw 21, and the said screw, through the medium of the spring 14, is normally forced into engagement with the teeth 105 110

4 of the shank 3. The portion of the member 18 provided with the screw 21 may be referred to as the body of the screw carrying member, and the said body is centrally formed with a longitudinally extending tail 22. The inner wall or tail is arranged at an angle to the body, the said wall being designated by the numeral 23 and is adapted to contact with the outer face of the bridge 11 to properly retain the screw 21 with relation to the teeth of the shank 3. The tail is bifurcated at its outer end, and one of the members formed by the bifurcation is provided with an elongated slot 24.

15 The numeral 25 designates the lock or latch of the member 18. The latch comprises a tongue 26, and sides 27. The top is adapted to be received within the bifurcation of the tail so as to permit of the longitudinal movement of the said catch upon the tail. The sides 27 are provided with a transversely arranged pin 28 which passes through the elongated slot 24 and which secures the latch for longitudinal movement upon the tail of the screw carrying member. The arms are formed at its lower ends with projecting fingers 29, and the said fingers, when the latch is moved to lock the member 18 upon the movable jaw, are received within the notched portions 12 provided upon the sides of the movable jaw.

20 From the above description taken in connection with the drawings the simplicity of the device as well as the advantages thereof

will, it is thought, be perfectly apparent to those skilled in the art to which such invention appertains without further detailed description.

Having thus described the invention, what I claim is:

40 In a wrench, a movable jaw provided with a toothed shank, a second jaw mounted for 45 slideable movement upon the shank, said jaw having its end notched, said jaw being provided with a pocket, a helical spring within the pocket, a pivoted member secured to the movable jaw and having a headed member engaged by the spring, said member including a body having a transverse opening, a screw journaled within the opening and 50 co-acting with the teeth of the shank, the body having one of its ends formed with a tail which is bifurcated and which has an elongated slot, a latch embodying a top and side members, the top being arranged within the bifurcated portion of the tail, a pin passing through the sides and through the elongated slot of the tail, and the sides having extending fingers which are adapted to be received within the notched portion of the movable 55 jaw when the pivoted screw carrying member is to be locked upon the said jaw.

56 In testimony whereof I affix my signature in presence of two witnesses.

OLLIE MULLINS.
